PHONOGRAPH BRAKE MECHANISM

John H. Teaf, Camden, N. J., assignor to Radio Corporation of America, a corporation of Delaware

Application November 26, 1932
Serial No. 644,451

15 Claims. (Cl. 192—117)

The present invention relates to automatic stopping and starting devices for phonographs. More specifically, the invention resides in a brake releasing and restoring member whereby 5 a control mechanism, such as is disclosed in the co-pending application of B. R. Carson, Serial No. 620,193, filed June 30, 1932, and assigned to Radio Corporation of America, for example, may be utilized in small, compact, portable 10 phonographs.

In portable phonographs of known types which are provided with automatically actuated brake mechanism, the size of the casing, in which the phonograph mechanism is housed, is usually so 15 chosen that the closing of the casing cover or lid will not interfere with a brake releasing and restoring member, carried by the tone arm, after the said tone arm has been placed in storage position preparatory to closing the lid of the 20 casing.

However, in order that a much smaller casing may be employed in the construction of a portable phonograph, without sacrificing any of the desirable features and advantages of the 25 automatically actuated stopping and starting mechanism, it is desirable that the brake releasing and restoring member operable by and in conjunction with the tone arm, be so modified and arranged that the said member will not 30 project beyond the marginal edge of the casing upon movement of the tone arm to storage position. Obviously, the use of a brake releasing and restoring member as shown in the co-pending application herein identified in connection 35 with a much smaller casing would result in the projection of the brake releasing and restoring member beyond the edge of the casing upon movement of the tone arm to storage position and prevent the proper closing of the casing 40 cover or lid.

It is, therefore, a primary object of the invention to provide a tone arm forming a part of a portable phonograph with a brake releasing and restoring member which is so positioned 45 automatically upon movement of the tone arm to storage position that a much smaller casing may be employed.

A further object of the invention is to provide a tone arm forming a part of a portable phonograph with a brake releasing and restoring member the position of which is automatically changed relatively to the tone arm upon movement of the tone arm to storage position.

Another object of the invention is to provide 55 a tone arm forming a part of a portable phono-

graph with a foldable brake releasing and restoring member whereby, when said arm is moved to storage position, said member will be so moved automatically as to occupy a position within the limits of the casing of said 60 phonograph.

A further object of the invention is to provide a tone arm forming a part of a portable phonograph which includes a brake mechanism with a foldable brake releasing and restoring 65 member which is adapted to be automatically retracted into a substantially vertical position upon movement of the tone arm to storage position.

Another object of the invention is to provide 70 the tone arm of a portable phonograph which includes an automatically actuated stopping and starting mechanism, with a control member for actuating said mechanism and means adapted to co-act with said control member upon movement 75 of said tone arm to storage position whereby said control member is moved relatively to said tone arm.

A further object of the invention is to provide 80 the tone arm of a portable phonograph which includes an automatically actuated brake mechanism with a yieldable brake actuating member which is adapted to be moved to a non-interfering position upon movement of the lid of said phonograph to closed position subsequent 85 to the movement of said tone arm to storage position.

With the above and other objects in view, the invention resides in the novel construction, combination, and arrangement of parts, the novel 90 features of which are set forth with particularity in the appended claims, the invention itself, however, both as to its organization and its method of operation, together with additional objects and advantages thereof, being best 95 understood from the following description of a specific embodiment, when taken in connection with the accompanying drawings, in which

Fig. 1 is a fragmentary plan view of a phonograph illustrating my invention as applied 100 thereto.

Fig. 2 is a view similar to Fig. 1 illustrating the position of certain parts when the tone arm is disposed in storage position.

Fig. 3 is a fragmentary view in elevation looking 105 in the direction of the arrows 3—3 of Fig. 2, and

Fig. 4 is a view similar to Fig. 3 illustrating another embodiment of my invention.

Referring to the drawings, I have illustrated, 110

by way of example, a phonograph which is provided with an automatic brake of the kind which is released for movement to "on" position by imparting to the tone arm, after 5 a period of sound reproduction, a movement in the reverse direction to that in which it is moved during sound reproduction and which may thereafter be restored to "off" position by moving the tone arm toward record starting position 10 from an outermost position of rest adjacent the periphery of the turntable.

Briefly, the brake mechanism, which is described and claimed in the herein identified co-pending application, includes a substantially 15 crescent shape base plate 10 which is provided with two spaced, upstanding pivot pins 11 and 12 whereby a spring influenced detent lever 13 and a spring influenced brake lever 14 may be 20 rotatably mounted on said base plate in co-operative relation. One free end of each of the levers 13 and 14 is adapted to co-act to maintain a brake pad 15, carried by the brake lever 14, out of engagement with a depending annular flange formed on the turntable 16. The 25 other end of the detent lever 13 is provided with an adjustably mounted toothed ratchet plate 17 which is adapted to co-act with a releasing and restoring member, forming the subject matter of the present invention, whereby the detent 30 lever 13 is tripped to release the brake lever 14 for movement to "on" position.

In its brake restoring movement, an element carried by the brake releasing and restoring member is adapted to co-operate with a cam-like projection 18 formed on one edge of the 35 brake lever 14 whereby said brake lever is restored to "off" position upon movement of the tone arm 19 toward record playing position.

In accordance with my invention, a brake releasing and restoring member which is adapted 40 to co-operate with the ratchet plate 17 and the cam-like projection 18, forming a part of the brake mechanism herein shown and described, for example, comprises a radially extending arm 45 which is hingedly connected to the periphery of a swivelled collar 21, forming a part of a tone arm mounting base 22, by means of a pair of co-operating hinge brackets 23 and 24.

The hinge bracket 23 comprises an arcuately 50 formed intermediate portion 25 and angularly bent, parallel, spaced end portions 26 which are suitably apertured for the reception of a hinge pin 27. A laterally extending tab 28, which serves as a stop member, is formed on the lower 55 edge of the intermediate portion 25 and centrally between the end portions 26. The intermediate portion 25 is also provided with suitable spaced apertures whereby the bracket 23 is adapted to be secured to the periphery of the 60 swivelled collar 21 by means of the screws 29 or the like.

A similar bracket 24 comprises a straight intermediate portion 30 which has one of its edges bent at right angles thereto to provide an up-standing ridge 31, and similarly bent, parallel, spaced end portions 32 which are also apertured for the reception of the hinge pin 27. The end portions 32 of the bracket 24 are spaced a greater distance apart so that the end portions 26 of the bracket 23 may be positioned therebetween and the hinge pin 27 passed through the apertures formed in the respective end portions 26 and 32, and the ends of the hinge pin 27 suitably peened to prevent longitudinal move-

ment thereof whereby the brackets 23 and 24 are hingedly connected.

A coiled spring 33 is disposed between the end portions 26 of the bracket 23 and about the hinge pin 27 in the assembly of the brackets 23 and 24 with one end of the spring 33 suitably attached to one of the end portions of the bracket 23 and its other end suitably tensioned against one edge of the intermediate portion of the bracket 24 whereby the hinge bracket 24 is constantly urged 85 downwardly with its upstanding ridge 31 in abutment with the laterally extending tab 28 on the bracket 23, as clearly shown in Fig. 1.

One end of the radially extending arm 20, comprising the brake releasing and restoring member, is secured to and centrally of the intermediate portion 30 of the hinge bracket 24 by means of a suitable rivet or the like with the secured end of the arm 20 in abutment with the upstanding ridge 31 formed on the said intermediate portion 30, whereby the arm 20 is held in T-shape formation with the hinge bracket 24 and against movement relatively thereto, as clearly shown in Fig. 1.

A pawl 35 is rotatably mounted on the free end of the radially extending arm 20 by means of a suitable pivot pin 34, a vertically disposed knife edge 36 formed on the outer end of said pawl being adapted to engage with the toothed edge of the ratchet plate 17, hereinbefore described. The other end of the pawl 35 is provided with an upstanding pin 37 having a squared end portion which projects through an arcuate slot 38 formed in the arm 20 on a radius with respect to the center of the pivot pin 34 so that the pin 37 will follow the contour of the slot 38 as the pawl 35 swings about the pivot pin 34.

The pawl 35 is normally urged in a clockwise direction by means of a spring 39 having one end thereof attached to the pawl 35, as indicated at 40, and the other end thereof attached to a depending ear 41 which is formed on one edge of the arm 20.

The means for moving the hinged radially extending arm 20 relatively to a tone arm 19, which is pivotally attached, at one end, to the swivelled collar 21 in a manner well known in the art, will now be described.

A cam member 42 which is adapted to be secured to the tone arm mounting base 22, by means of one of a plurality of screws 43 usually employed to secure the base 22 to a transverse member or motorboard 44, comprises an up-standing substantially L-shape member which terminates in a transversely extending edge portion 45 defining two angularly related edge portions 46 and 47 which are adapted to co-operate successively with the upstanding ridge 31, formed on the hinge bracket 24, upon movement of the tone arm 19 to storage position in a suitable supporting clip "C" therefor, as illustrated in Fig. 2.

Simultaneously with the manual movement, for example, of the tone arm 19 from a normal 140 operative position toward a storage position indicated in Fig. 2, the bracket 24 contacts with the edge portion 46 of the cam member 42 to begin the swinging movement of the brake releasing and restoring member 20 about its pivot 145 and against the action of the spring 33. As this movement of the tone arm 19 is continued, the hinge bracket 24 next contacts with the edge portion 47 of the cam member 42 to complete the swinging movement of the brake releasing and 150

restoring member 20, relatively to the tone arm 19, to a substantially vertical position whereupon the casing closure cover or lid 48 may be properly moved to closed position without interfering 5 with the brake releasing and restoring member 20.

In an alternative embodiment of the invention, illustrated in Fig. 4, for example, the cam member 42 may, under certain conditions, be dispensed with and the rear vertical side 49 of the lid 48 relied upon to co-act with the brake releasing and restoring arm 20, when it projects beyond the rear edge 50 of the phonograph casing 51 upon movement of the tone arm 19 to storage position, and elevate the arm 20 in the direction of the arrows in Fig. 4 sufficiently to prevent the arm 20 from interfering with the lid 48 upon movement thereof toward closed position.

20 Although I have shown and described certain specific embodiments of my invention, I am fully aware that many modifications thereof are possible. My invention, therefore, is not to be restricted except insofar as is necessitated by the prior art and by the spirit of the appended claims.

I claim as my invention:

1. In a phonograph, the combination of a rotatable element, brake mechanism for said element, a pivoted element including a support therefor having forward and reverse movements, means carried by said pivoted element adapted for actuating said mechanism, and means associated with said support whereby said first-named means is movable relatively to said pivoted element upon movement of said element to a storage position.

2. In a phonograph including a brake, a swingable tone arm and a support therefor, brake actuating means associated with said tone arm, and means carried by said support whereby said brake actuating means is adapted to be moved relatively to said tone arm upon movement thereof to storage position.

45 3. In a phonograph including brake mechanism, a swingable tone arm and a support therefor, means associated with said tone arm adapted for actuating said brake mechanism upon limited movement of said tone arm in one direction, and means carried by said support whereby said first-named means is moved relatively to said tone arm upon movement thereof in a direction opposite to said first named direction.

55 4. In a phonograph including automatically actuated brake mechanism, a swingable tone arm and a support therefor, brake releasing and restoring means associated with said tone arm and adapted for actuating said brake mechanism, and means carried by said support whereby said brake releasing and restoring means is moved simultaneously relatively to said tone arm upon movement thereof to a storage position.

5. In a phonograph, the combination with a rotatable support, brake mechanism for said support, a pivoted tone arm adapted to be moved to a storage position and including a supporting base therefor, of a brake releasing and restoring member hingedly connected to said tone arm for movement in conjunction therewith, and cam means carried by said base adapted to co-operatively engage said brake releasing and restoring member upon movement of said tone arm to storage position whereby said member is moved relatively to said tone arm simultaneously.

75 6. In a phonograph including a brake and a

swingable tone arm adapted to be moved to storage position and a supporting base therefor, a brake actuating member hingedly connected to said tone arm and normally extending radially therefrom, and means associated with said base adapted to engage said actuating member upon movement of said tone arm to storage position whereby said actuating member is simultaneously retracted relatively thereto.

7. In a phonograph including a brake and a swingable tone arm adapted to be moved to storage position and a supporting base therefor, a brake actuating member hingedly connected to said tone arm and normally extending radially therefrom, means associated with said base adapted to engage said actuating member upon movement of said tone arm to storage position whereby said actuating member is simultaneously retracted relatively thereto, and means associated with said actuating member for restoring said member to normal position upon movement of said tone arm to operative position.

8. In a phonograph, the combination with a rotatable support, brake mechanism for said support, a tone arm adapted to be moved to a storage position, a support for pivotally mounting said tone arm, of brake actuating means associated with said tone arm and adapted to be moved in conjunction with and relatively to said tone arm simultaneously, and means carried by said support whereby said brake actuating means is moved relatively to said tone arm upon movement thereof to storage position.

9. The combination with a phonograph including brake mechanism, a swingable tone arm adapted to be moved to storage position, and a supporting base for said tone arm, of a brake releasing and restoring lever hingedly connected to said tone arm and normally extending radially therefrom, a cam-like member secured to said base in the path of a hinge element forming a part of said actuating lever whereby, when said tone arm is moved to storage position, said cam-like member will co-act with said hinge element to move said lever relatively to said tone arm, and means for restoring said lever to normal position upon movement of said tone arm to operative position.

10. In a phonograph, the combination with a casing, a cover movable relatively thereto and a swingable tone arm adapted to be moved to a storage position in said casing of a control lever yieldably connected to said tone arm radially thereof for movement in conjunction therewith whereby, when said tone arm is moved to storage position, said lever will project outwardly of said casing and partly into said cover, said cover and said lever being adapted to co-operate upon movement of said cover to closed position to move said lever relatively to said tone arm.

11. In a phonograph, the combination with a portable casing, a cover movable relatively thereto and a swingable tone arm adapted to be moved to a storage position in said casing of a brake actuating lever hingedly connected to said tone arm and normally extending radially therefrom for movement in conjunction therewith whereby, when said tone arm is moved to storage position, said lever will project outwardly of said casing partly into said cover, said cover and said lever being adapted to co-operate upon movement of said cover to closed position to move said lever relatively to said tone arm.

12. In a phonograph, a reproducer support susceptible of movement from operative to stor-

age position, trip mechanism carried by said support, means tending to impede movement of said mechanism into storage position, and means whereby, when said support is moved to storage position, said trip mechanism is caused to avoid said movement impeding means.

13. In a phonograph, the combination of a rotatable element, stop mechanism for said element, a pivoted element including a support therefor having forward and reverse movements, means carried by said pivoted element adapted for actuating said mechanism, and means associated with said support whereby said first-named means is movable relatively to said pivoted element upon movement of said element to a position to one side of said rotatable element.

14. In a phonograph including stop mechanism, a swingable tone arm and a support there-

for, means associated with said tone arm adapted for actuating said stop mechanism upon limited movement of said tone arm in one direction, and means carried by said support whereby said first named means is moved relatively to said tone arm upon movement thereof in a direction opposite to said first named direction.

15. In a phonograph including automatically actuated stop mechanism, a swingable tone arm and a support therefor, stop releasing and restoring means associated with said tone arm and adapted for actuating said stop mechanism, and means carried by said support whereby said stop releasing and restoring means is moved simultaneously relatively to said tone arm upon movement thereof to an inoperative position.
